WEFT REPLENISHING MECHANISM FOR
OVAL BOBBINS

Richard Greenleaf Turner, Worcester, Mass., assignor to Crompton & Knowles Loom Works, Worcester, Mass., a corporation of Massachusetts

Application August 26, 1936, Serial No. 97,967

10 Claims. (Cl. 139—243)

This invention relates to improvements in weft replenishing looms operating with oval bobbins and it is the general object of the invention to provide means whereby the bobbin can be correctly positioned in the shuttle at the conclusion of the transferring operation.

It has been common practice for many years to transfer bobbins the weft packages of which are cylindrical and circular in cross section, mechanisms having been devised to transfer such bobbins both in single and multicolor types of looms. Because of the fact that the horizontal dimension of the shed is greater than the vertical dimension it is possible to weave with a shuttle wider than those heretofore employed and to provide the shuttle with a bobbin the vertical diameter of which is substantially the same as that of the previously used circular bobbins, but the horizontal diameter of which is considerably greater than that formerly used. The weft in such a shuttle is wound on a bobbin the cross-section of the barrel of which has a horizontal dimension greater than its vertical diameter and in order that the bobbin may be held so that its major cross section dimension will not extend below the shuttle provision must be made to insert it into the shuttle with the long axis horizontal.

In the transfer mechanisms heretofore employed there has been no need for placing the bobbin in any particular angular position relatively to the shed and the transerrer arms have been provided with a spool having a concave surface substantially arcuate in transverse cross section for engagement with the bobbin being inserted into the shuttle. Furthermore, it is common practice to employ a pivoted transerrer arm moving about an axis in front of the lay so that downward movement of the arm and spoon changes the angular relation of these parts with respect to a horizontal plane. Under prior practice this condition was immaterial but when applied to a magazine operating with oval bobbins it is necessary to take into account the change of angular relation on the part of the transerrer arm during transfer.

It is an important object of my present invention to provide a transerrer arm and magazine so constructed that the reserve bobbins are held with the major transverse weft axis oblique with respect to a horizontal plane, the obliquity bearing a definite relation to and being preferably the same as the angle through which the transerrer arm moves. In carrying my present invention into effect I provide the spoon of the

transerrer arm with a substantially flat surface which is inclined downwardly and forwardly at such an angle that as transfer is completed said surface becomes horizontal. In this way the oval bobbin is inserted into the shuttle in the proper position.

It is a further object of my present invention to provide an improved form of yielding bobbin tip support so constructed as to maintain the bobbin in the magazine with its major transverse axis tilted so that when the bobbins are presented to the transfer arm they will be in the desired position.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a vertical transverse section through a weft magazine and lay having the bobbins and transerrer arm arranged and constructed according to my present invention,

Fig. 2 is a front elevation of the magazine and adjacent lay and on a scale somewhat smaller than that shown in Fig. 1, part of the structure being in section,

Fig. 3 is a view similar to the lower part of Fig. 2 on an enlarged scale, parts being in section,

Fig. 4 is a view similar to a portion of Fig. 1 but with the transerrer arm shown at the end of its transferring stroke, and

Fig. 5 is a detailed vertical section on line 5—5 of Fig. 3.

Referring to the drawing, the loom frame 10 supports a magazine M over the lay L. The latter is provided with a slot 11 through which exhausted bobbins may be expelled from a shuttle 40 S located in a shuttle box 12. The shuttle has spring clips 13 which hold the circular rings 14 of the bobbin butt 15 formed at one end of the bobbin B. The horizontal transverse axis of the barrel or weft carrying part of the bobbin 16 and tip 17 is elongated, as shown clearly in Figs. 1, 4 and 5.

The magazine comprises a fixed housing 20 supporting a stud 21 on which is rotatably mounted the hub 22 of a rotary bobbin support- 50 ing disk 23 having sockets 24 to receive the rounded ends of the bobbin butts 15. A ratchet 25 is rigid with the disk 23 and cooperates with a feed pawl 26 in well-known manner to effect an advance of the disk 23 in a clockwise direc- 55

tion as viewed in Fig. 1 at each transferring operation of the loom. A holding pawl 27 may also be provided to retain the magazine in correct angular position for transfer.

5 A second or bobbin tip supporting disk 30 is secured to the hub 22 and rotates therewith and is provided with a series of slots 31 for each of which there is provided a yielding tip support 32. The disk 30 has a plurality of lugs 33 to receive 10 the complementarily formed ends 34 of the supports 32, and each of the latter is urged inwardly or toward the bobbin by a compression spring 35. Inward motion of the support 32 may be limited by a rib 36 on the disk 30. A thread holder 37 15 may rotate with the disks. The matter thus far described is of common construction and of itself forms no part of my present invention.

The transferrer arm 40 is pivoted about a stud 41 fixed to the magazine frame, and has a de- 20 pending arm 42 on which is pivoted a transferrer latch 43 to engage a bunter 44 projecting forwardly from the lay L. Control mechanism for the latch 43 is omitted from the drawing but is well understood and when a transfer operation 25 is called the latch 43 will be raised into the path of the bunter 44 to cause downward motion of the transferrer arm as the lay advances. That part of the transferrer arm thus far described is also old and of itself forms no part of my present 30 invention, the transferrer arm carrying the previously described feed pawl 26.

In carrying my invention into effect I provide each of the supports 32 with a pocket 50 having therearound a rib 51 the upper part 52 of which 35 is inclined with respect to a horizontal line when the associated support arrives under the transferrer arm. The pocket is so constructed as to receive the flattened tip end of the bobbin and the vertical surface 53 of the pocket is inclined 40 slightly inwardly so as to hold the bobbin tip 17 in place, see Fig. 3. This inclined surface may if desired be formed as though generated by a line rotating about the transferrer stud 41 and moving inwardly toward the disk 23 as it descends. Such 45 a construction will favor the correct motion on the part of the bobbins as they are transferred. The front wall 55 of the pocket rib 51 is curved to accommodate the arcuate motion of the bobbin during transfer.

50 The magazine is supplied with a plurality of the bobbins B and it will be noted that since their major transverse axes are oblique with respect to radial lines emanating from the stud 21 it is possible to accommodate a greater number of bobbins than would be the case were the major transverse dimension perpendicular to a radius from stud 21. As the pawl 26 actuates the ratchet 25 the magazine acts to present the reserve bobbins successively to transfer position, 55 and the latter is determined by the position of the shuttle when the lay is on front center. A bobbin butt guide 57 similar to those heretofore used may be employed to assist in directing a bobbin moving from the magazine into the shuttle.

60 The bobbin butt 15 is preferably circular in cross section so that the transferrer arm heel 60 which engages the butt end of the bobbin may be concave on the underside thereof, as is usual. A spoon 61 is provided with a flat under surface 62 which is inclined downwardly and forwardly as indicated in Fig. 1 when the transferrer arm is in its normal raised position. The angle between this surface 62 and a horizontal 70 line is preferably the same as that through which

the transferrer arm swings during a transfer operation. The spoon 61 may have a shank 63 by which it is attached to the transferrer arm 40 and the surface 62 is adapted for engagement with the upper flattened weft area 65 of the bobbin 5 being transferred. A weft detector F is indicated in Fig. 1 and acts to indicate exhaustion of weft and call a transfer operation of the loom.

In operation, when a transfer is called, the transfer arm will descend, the heel engaging the butt of the bobbin and the surface 62 of the spoon engaging the upper surface 65 of the bobbin immediately thereunder. As the lay advances the transferrer arm moves about the stud 41 as a center and the angular position of the surface 62 15 approaches the horizontal and at the end of the transferring stroke surface 62 will be substantially horizontal, as in Fig. 4.

From the foregoing it will be seen that I have provided means whereby an oval bobbin can be 20 correctly transferred into a shuttle. This result is achieved by having the major transverse axis of the bobbin barrel oblique at the start of the transfer motion, the obliquity being sufficient to cause the bobbin to assume a correct horizontal 25 position when in the shuttle. The angle which the said major axis sustains to a horizontal line may be substantially the same as that through which the transferrer arm swings. It will further be seen that the bobbin tip supports are so 30 formed as to maintain the bobbins in correct angular position and the method of generating the bottom of the support pocket which remains in contact with the bobbin tip throughout the first part of the downward motion of the bobbin 35 further assists in correct delivery of the bobbin to the shuttle. It will also be seen that the bobbin is prevented from having any appreciable angular motion relatively to the transferrer arm during transfer due to the shape of the spoon.

Having thus described my invention it will be seen that changes and modifications may be made therein by those skilled in the art without departing from the spirit and scope of the invention and I do not wish to be limited to the 45 details herein disclosed, but what I claim is:

1. In a weft replenishing loom operating with oval bobbins having a mass of weft with a major horizontal transverse dimension greater than the vertical transverse dimension thereof and having 50 a shuttle, a magazine for reserve oval bobbins, a transferrer arm to move a bobbin from the magazine into the shuttle, means in the magazine to hold a reserve bobbin in transfer position in the magazine with the major transverse axis thereof inclined with respect to a horizontal plane, and means on the transferrer arm having a surface 55 also inclined with respect to a horizontal plane to engage the upper part of the weft of a reserve bobbin, the inclination being such that when 60 the bobbin and last named means reach their lowest position the said major axis of the bobbin and the surface of the last named means will be substantially horizontal.

2. In a weft replenishing loom operating with 65 oval bobbins having a mass of weft with a horizontal transverse dimension greater than the vertical transverse dimension and having a shuttle, a magazine for reserve oval bobbins, a transferrer arm to move a bobbin from the 70 magazine into the shuttle, means defining an axis about which the transferrer arm swings, means forming part of the magazine to present a reserve bobbin in position for transfer with the major transverse axis thereof inclined down- 75

wardly and toward said axis, and a spoon on the transferrer arm having a surface inclined downwardly and toward said axis to engage the upper flattened surface of the weft of a reserve bobbin to be transferred, the inclination of said axis of the bobbin and said surface of the spoon being such that at the end of the transfer stroke said axis and surface will be substantially horizontal due to angular movement about said axis.

10. 3. In a weft replenishing loom operating with oval bobbins having a mass of weft with a horizontal transverse dimension greater than the vertical transverse dimension and having a shuttle and lay, a magazine for reserve oval bobbins, a transferrer arm to move a bobbin from the magazine into the shuttle, means defining an axis about which the transferrer arm swings, means to connect the lay and transferrer arm to cause the latter to move through a given angle 15 to effect transfer, means to hold a reserve bobbin in position for transfer with the major transverse axis thereof inclined with respect to a horizontal plane by an amount equal substantially to said angle, and a spoon on the transferrer arm 20 having a surface at substantially said given angle with respect to a horizontal plane to engage the upper surface of the weft of a reserve bobbin being transferred, the transferrer arm when swinging through said angle about the axis thereof causing said surface to turn the bobbin about the longitudinal axis thereof through substantially said given angles and cause the aforesaid transverse axis of the bobbin to be horizontal 25 at the end of the transfer stroke.

35. 4. In a weft replenishing loom having a shuttle to be replenished, a pivoted transferrer arm movable through a given angle to effect replenishment of the shuttle, an oval bobbin having a mass of weft with one transverse dimension greater than the other, means to hold the bobbin in transfer position with said one greater transverse dimension at an angle with respect to the horizontal plane substantially equal to the aforesaid angle through which the transferrer arm moves, and means on the transferrer arm to extend transversely across the upper surface of a bobbin to be transferred and engage the weft and cause movement of the bobbin about the longitudinal axis thereof through an angle substantially equal to said given angle between the beginning and the ending of the transfer stroke.

50. 5. In a weft replenishing loom operating with oval bobbins having a mass of weft with a horizontal transverse axis greater than the vertical transverse axis, a pivoted transferrer arm to swing through a given angle to effect transfer, a shuttle to receive a reserve bobbin, means to present a reserve bobbin into transfer position for engagement with the transferrer arm so that the greater transverse axis of said bobbin is inclined with respect to the final position which said bobbin is to sustain to the shuttle by the aforesaid angle, and means carried by the transferrer arm to engage the weft and prevent substantially relative angular motion between the transferrer arm and said greater transverse axis of the bobbin during transfer.

65. 6. In a weft replenishing loom operating with oval bobbins having a major horizontal transverse axis greater than the vertical transverse axis, a pivoted transferrer arm having a bobbin engaging surface inclined with respect to the horizontal at the beginning of a transferring operation, said surface changing its angle with respect to a horizontal plane when the transferrer

arm moves about its axis during the transferring operation, and means to present a reserve oval bobbin in transfer position with the major transverse axis thereof inclined with respect to a horizontal plane by an amount substantially the same as the inclination of said surface, the inclination of said surface and major axis being such that at the end of the transferring stroke said major axis is substantially horizontal.

7. In a weft replenishing loom operating with oval bobbins having a weft mass with a major transverse horizontal axis which is greater than the vertical transverse axis, a shuttle to receive a reserve oval bobbin, a transferrer arm, a pivot about which the transferrer arm swings during transfer, means on the transferrer arm to engage the flattened part of the weft to resist rotation of the bobbin being transferred about the longitudinal axis thereof relatively to the transferrer arm during transfer, and means to hold a reserve bobbin in transfer position with the major transverse axis thereof inclined at such an angle that as the transferrer arm reaches the end of the transfer stroke after moving through a given angular distance the major transverse axis of the bobbin will be substantially horizontal.

8. In a weft replenishing loom, a reserve weft magazine operating with oval bobbins each having a barrel and tip with a major horizontal transverse axis greater than the vertical transverse axis thereof, a yielding support for the tip forming part of the magazine and having an inclined surface to hold and position a reserve oval bobbin in transfer position with its major transverse axis inclined with respect to the horizontal, and a transferrer arm being moved through a given angle to effect transfer, the angle between a horizontal plane and said surface of the support being substantially the same as said given angle.

9. In a weft replenishing loom, a reserve weft magazine operating with oval bobbins each having a barrel and tip with a major horizontal transverse axis greater than the vertical transverse axis thereof, a pivoted transferrer arm moving through a given angle to effect transfer, a yielding support for the tip of the reserve bobbin to be transferred, said support having a pocket for the tip end of the bobbin and the top of the pocket being formed to position a bobbin in transfer position with the major transverse axis thereof angularly disposed with respect to a horizontal plane at an angle substantially the same as said given angle through which the transferrer arm moves.

10. In a weft replenishing loom, a reserve weft magazine operating with oval bobbins each having a barrel and tip with a major horizontal transverse axis greater than the vertical transverse axis thereof, a pivoted transferrer arm moving through a given angle to effect transfer, a yieldable support for the tip of the reserve bobbin to be transferred, said support having a pocket for the tip end of the bobbin and the top of the pocket being formed to position a bobbin in transfer position with the major transverse horizontal axis thereof angularly disposed with respect to a horizontal plane at an angle substantially the same as said given angle through which the transferrer arm moves, the side of the pocket being generated by a line substantially parallel to the top of the pocket and moving about the axis of the transferrer arm.
